UNITED STATES PATENT OFFICE.

PETAR HABRICH, OF PHILADELPHIA, PENNSYLVANIA.

LIFE-SUSTAINING APPARATUS.

1,394,824.

Specification of Letters Patent. Patented Oct. 25, 1921.

Application filed November 1, 1920. Serial No. 421,011.

To all whom it may concern:

Be it known that I, PETAR HABRICH, a citizen of Austria, residing at Philadelphia, in the county of Philadelphia and State of Pennsylvania, have invented certain new and useful Improvements in Life-Sustaining Apparatus, of which the following is a specification.

It is well known that persons on a sinking ship are often compelled to take to the water in an effort to save their lives. After entering the water and after the ship sinks unless these persons are quickly picked up by a passing ship, they will soon perish.

15 One object of my invention is to provide improved apparatus of such character that when used will be the means of sustaining the lives of such persons for a long time.

Another object is to construct my improved apparatus in such manner that it will be serviceable in stormy weather as well as in fair weather.

Another object is to provide means which will enable the persons, even though in the water, to signal for aid.

These objects, and other advantageous ends which will be described hereinafter, I attain in the following manner reference being had to the accompanying drawings

30 in which—

Figure 1 is a side elevation of one form of my improved apparatus illustrated partly in section and in the position which it will assume when in the water,

35 Fig. 2 is a top plan view of the apparatus shown in Fig. 1 illustrating the same connected to a life preserver which may be attached to a person who may be termed the attendant of the apparatus,

40 Fig. 3 is an enlarged fragmentary section taken on the line 3—3 of Fig. 2,

Fig. 4 is a view of the same general character as that shown in Fig. 3 showing the parts in a position to permit the hand of the attendant to be inserted into the supply buoy for the purpose of removing food for distribution to other persons who are also in the water and supported by life preserving belts (not illustrated),

45 Fig. 5 is an enlarged fragmentary section taken on the line 5—5 of Fig. 2 and illustrating a waterproof electric button operative to produce a signal,

50 Fig. 6 is a view of the same general character as that shown in Fig. 1 illustrating a modified form of my invention,

Fig. 7 is a front elevation showing a modified form of my invention as applied to and supported by a life preserving belt which may be attached to a person in the water, 60 and Fig. 8 is a side view of Fig. 7; a part of the structure being illustrated in section.

Referring to the drawings and particularly to Figs. 1 to 5 inclusive, my improved apparatus includes a supply buoy 9 which 65 consists of a container 10 having a frustoconical portion 11 which tapers downwardly and joins a cylindrical part 12 which is closed at its end with a cap 13. This entire container below the top plate 14 is incased 70 in a cork shell 15 as clearly shown in Fig. 1. A tank 16 is mounted within the cylindrical part 12 and a tube 17 leads upwardly from the tank and is connected to a nipple 18 located outside of the container and normally closed by a cap 19 the latter being 75 screwed on the nipple 18 which is connected by a chain 20 to the nipple 18 to prevent its loss when the cap 18 is removed to supply drinking water as will hereinafter be described. The tube 17 between the top plate 14 and the tank 16 is inclosed in a hose 21 which also communicates with the interior of the tank 16 at its top; said hose 21 at a space within the container above the partition 22 being provided with an air inlet 80 hole 21^a so that when any of the water is sucked out of the tank 16 through the tube 17, the amount of water removed from the tank will be replaced with air so as to permit the drinking water to be easily sucked 85 through the tube 17. The space 23 above the tank 16 may be used to include an electric battery 24 for signaling purposes hereinafter described.

90 An air conducting pipe 25 is mounted in an upright position projecting a considerable distance above the top plate 14; said air conducting pipe being made in two sections coupled by a union 26; the lower section being mounted within the container on a bracket 27 as clearly shown in Fig. 1. The top of the pipe 25 extends within a housing 28; said housing inclosing the top of the pipe 25 and including baffles 29 mounted above its open 95 end 30 so that air entering the open end will be supplied to the top of the pipe 25 and under certain conditions will pass downwardly into the container 10 as indicated by the arrows. The baffles 29 serve to prevent any water which splashes upwardly through the open end 30 of the housing from passing

100

105

110

downward through the pipe 25 and I preferably connect cables 31 to the top of the housing and to the top plate 14 in order to brace the air conducting standard which includes 5 the pipe 25 and the housing 28. An air outlet tower 32 is mounted on the plate 14 and at its bottom communicates with the interior of the container 10. This tower has a number of nipples 33 to which flexible tubes 34 10 are attached; said flexible tubes being supported at positions remote from the buoy 9 by floats 35^a which are preferably made of cork so as to float in the water. These tubes 34 are extended as shown at 35 and preferably 15 provided with a mouth piece 36 so that a person can by the aid of an elastic band 37 attach the mouth piece to the head so that air can be breathed through the tubes 34. The tower 32 includes an opening 38 to permit 20 air to directly enter from the atmosphere and a pipe 39 extends downwardly through the opening and also communicates with the nipples 33.

Any suitable baffle, such for example as 25 shown at 40, can be employed in a similar capacity to the baffles 29 above described to prevent water entering the tower through the opening 39 from passing downwardly through the pipe 39 to the nipples 33. I 30 have only illustrated one of the tubes 34 leading from the tower 32 but it will be understood that there may be as many tubes 34 as there are nipples 33 and one of the nipples 33 can be used to connect a tube 34^a, as 35 shown in Fig. 2, to supply air to the person who is attending the buoy 9. The buoy 9 is preferably provided with straps 41 which may have any suitable attaching means thereon such for example as the hooks 42 40 which are adapted to engage in connecting rings 43 on a life preserving belt 44, as shown in Fig. 2; said life preserving belt 44 surrounding the body of the attendant of the buoy. Thus the attendant can keep the buoy 45 within reach for the purpose of supplying drinking water to any of the persons surrounding the buoy, and can dispose of the food at intervals by inserting his hand downwardly through a flexible shield 45 50 which extends into the container 10 through an opening 46 in the top plate 14. The shield 45 may be made of sheet rubber having an opening 47 of such normal diameter as to compel the hand to be forced there- 55 through and then contract around the wrist as shown in Fig. 4. Thus the attendant can insert his hand and withdraw food without possibility of water entering the container as is obvious from the illustration in Figs. 60 3 and 4.

A door 48 is hinged at 49 and is adapted to close the opening 46 and form a cover for the shield 45. This door is adapted to be locked in position by pivot bolts 50 which 65 can be swung into notches in the door 48

after which clamping nuts 52 can be tightened and securely hold the door in position to prevent water from accidentally working its way into the container. If, however, any water should accidentally work its way into 70 the space 23, the same can be withdrawn by the attendant sucking through the tube 53; said tube 53 leading into the buoy through the top plate 14 and extending into the compartment 23 as shown in Fig. 1. This tube 75 53 below the partition 22 is inclosed in a hose 54, the upper end of which is connected to a nipple 55 leading downwardly from the partition 52; said nipple being of such internal diameter as to communicate with the 80 interior of the container 10 so that when the water is drawn out through the tube 53, the amount of water drawn from the space or compartment 23 will be replaced by air entering the compartment through the medium 85 of the hose 54. It will be understood that both the hose 21 and the hose 54 are of larger internal diameter than the external 90 diameter of the tubes which pass through them so that an air space is provided between the tube and the hose in each instance.

The top plate 14 has a search light 56 pivotally mounted thereon so that if the apparatus is used at night the search light can be moved by the attendant to illuminate the 95 various floats 35^a to show any person just where these floats are located so that persons, if the water is too rough to prevent free breathing, can stay near the floats and breathe through the tubes 34. Each of the 100 tubes 34 has pipes 57 which lead downwardly to receptacles 58 so that if any water enters the tubes 34 through the mouth pieces 36, this water will drain down into the receptacles 58 instead of being backed into the 105 tower 32 and I preferably provide a suction tube 59 for each receptacle 58 whereby the water can be sucked out of the receptacles 58 from time to time. Furthermore the pipes 57 form a balancing means to keep the 110 floats 35^a in substantially horizontal positions while in the water and thus prevent the turning of the floats and thus keep all of the tubes 34 in proper positions. The air conducting standard, which includes the air 115 conducting pipe 25 and housing 28, supports at its top an electric lamp 60 which is connected with wires leading from the battery 24; said wires also including a push button 61 which is inclosed in a casing 62 120 having a rubber cap 63 stretched over its top as clearly shown in Fig. 5. Thus the attendant can effect the illumination of the lamp 60 merely by pushing down on the top of the rubber cap 63 and water will be 125 prevented from touching the button 61.

In the form of my invention shown in Fig. 6, I have illustrated a slight modification in the arrangement of certain of the parts. For example instead of providing 130

the air conducting pipe 25 with a housing at its top as described in connection with Figs. 1 to 5 inclusive, the top of the air conducting pipe 25^a is provided with a wide funnel end 64 which provides an opening for the entrance of air and this entrance may be closed by a door 65 which is hinged at 66 to the bottom of the funnel end 64 and a cable is attached to the top of the door 65 and leads downwardly to a cleat 68 on the pipe 25^a in reach of the attendant so that the amount of air entering the funnel can be varied.

The buoy 9^a is made of a slightly different shape from that described in connection with the buoy 9 and has a space 69 which provides a compartment in which a container 70 is mounted which communicates with the bottom of the pipe 25^a and with the tower 32^a. The tower 32^a is constructed similarly to the tower 32 and instead of providing a suction tube for any water which might happen to enter the container, I provide an outlet passage or duct 71 which 25 provides a drain; it being understood that the displacement of the buoy 9^a is such that the surface of the water would always be below the bottom of the air pipe 25^a. The other parts illustrated in Fig. 6 are similar 30 to certain of the parts described in connection with Figs. 1 to 5 inclusive and I have therefore given similar parts corresponding reference characters.

In Figs. 7 and 8, I have illustrated an apparatus including an air conducting standard pipe 25^b which is secured to a container 10^a; the pipe 25^b extending below the container and adapted to be inserted within a socket provided by bars 72 pivotally mounted at 73 on a life preserving belt 74. The ends of the bars 72 opposite the pivots 73 being notched at 75 and adapted to engage over bolts 74; the ends of the bars 72 opposite the pivots 73 being notched at 75 and 45 adapted to engage over bolts 76; said bolts having thumb nuts 77 thereon adapted to tighten the bars and secure the device in upright position. The top of the air conducting tube has a housing 28^a of the same 50 general construction as that described in connection with the housing 28, and an electric lamp 60^a is supported above the housing and is operative by current supplied by a battery 24^a in the container 10^a. A push button 61^a is secured to the top of the container 10^a; said push button being constructed similarly to the push button 61 above described. The container 10^a may be used to provide space for food or drinking water 55 and as illustrated I have shown a tank 16^a for drinking water and a suction tube 17^a out of which the drinking water may be withdrawn. The air conducting pipe 25^b at a position within the container 10^a has a 60 hole 78 therein communicating with the in-

terior of the container and an air supply hose 34^a communicates with the interior of the container and may be used by the person wearing the life preserving belt 74 to breathe air through the medium of the 70 mouth piece 36^a. The container 10^a has an opening 79 which is normally closed by a cover 80 and the cover 80 can be removed to permit access to the interior of the container. In this form of my apparatus, the 75 life preserving belt 74 forms the buoy to support a person and also to support the container and the associated parts.

While I have described my invention as taking a particular form, it will be understood that the various parts of my invention may be changed without departing from the spirit thereof, and hence I do not limit myself to the precise construction set forth, but consider that I am at liberty to make 85 such changes and alterations as fairly come within the scope of the appended claims.

Having thus described my invention, what I claim as new and desire to secure by Letters Patent is:—

1. Apparatus of the character described including means providing an air reservoir; a breathing tube leading from said reservoir; an upright pipe leading upwardly from said reservoir; and a housing surrounding said pipe and open at its bottom, said pipe being in open communication with the interior of said housing above said open bottom; substantially as described. 90

2. Apparatus of the character described including means providing an air reservoir; a breathing tube leading from said reservoir; an upright pipe leading upwardly from said reservoir; a housing surrounding said pipe and open at its bottom, said pipe 100 being in open communication with the interior of said housing above said open bottom; and a baffle surrounding said pipe above said open bottom and located within said housing; substantially as described. 105

3. Apparatus of the character described including means providing an air reservoir; a breathing tube leading from said reservoir; an upright pipe leading upwardly from said reservoir; and a housing surrounding 115 said pipe and open at its bottom, said pipe being in open communication with the interior of said housing above said open bottom, said housing having a portion tapering downwardly to the opening in said bottom; 120 substantially as described.

4. Apparatus of the character described including means providing an air reservoir; a breathing tube leading from said reservoir; an upright pipe leading upwardly 125 from said reservoir; a housing surrounding said pipe and open at its bottom, said pipe being in open communication with the interior of said housing above said open bottom; and a baffle surrounding said pipe 130

above said open bottom and located within said housing, said baffle being frusto-conical and tapering downwardly; substantially as described.

5. Apparatus of the character described including a buoy; means for supplying air to the buoy to the exclusion of water; a float; a flexible hose supported by said buoy and float for conducting air from said buoy; and 10 a flexibly connected mouth piece supported by said float and in communication with said hose; substantially as described.

6. Apparatus of the character described including a buoy; a signal device thereon; 15 an electric generator carried by the buoy; and a push button switch supported by said buoy and in connection with said generator and said signal device, said push button switch having a flexible cap forming a seal 20 to prevent water from contacting with the parts of the switch, the button of said switch being operative through the medium of pressure upon said cap; substantially as described.

25 7. Apparatus of the character described

including a buoy having a storage space therein and an opening permitting access to said space; and a flexible shield connected around said opening and having a contracted hole therein to permit the insertion and removal of a hand into and out of said space to the exclusion of water; substantially as described.

8. Apparatus of the character described including a buoy having a storage space 35 therein; a tank for drinking water positioned within said space; a tube extending into said buoy and into said tank; a hose communicating with said tank and inclosing a portion of said tube, said hose having 40 an air inlet hole communicating with the space in said buoy; and means for supplying air to said space; substantially as described.

In testimony whereof I have signed my name to this specification in the presence of 45 two subscribing witnesses.

PETAR HABRICH.
